UNITED STATES PATENT OFFICE.

RUDOLF M. OSTERMANN, OF EVANSTON, ILLINOIS, ASSIGNOR TO LOCOMOTIVE SUPER-HEATER COMPANY, OF NEW YORK, N. Y., A CORPORATION OF DELAWARE.

LOCOMOTIVE ATTACHMENT.

1,323,406.

Specification of Letters Patent.

Patented Dec. 2, 1919.

Application filed September 14, 1917. Serial No. 191,386.

To all whom it may concern:

Be it known that I, RUDOLF M. OSTERMANN, a citizen of the United States, residing at Evanston, Illinois, have invented 5 certain new and useful Improvements in Locomotive Attachments, of which the following is a specification.

My invention relates to locomotives where- 10 in the steam is furnished to the cylinders in a superheated state, and provides means whereby the operating crew may be informed of the temperature of the steam entering the steam chest, and whereby steam is furnished to the valve chests independ- 15 ently of the supply governed by the main throttle.

The introduction of the use of superheated steam in locomotive practice has resulted in certain difficulties at times when the main 20 throttle is closed while the engine is running, or,—to use the word commonly employed among railway men,—when the engine is drifting. At such times the engine acts like a pump, tending to pump out of 25 the steam pipe and communicating spaces what steam is left on the closing of the throttle.

There is as a result of this pumping action 30 a partial vacuum in the cylinder at the moment the exhaust port is opened, so that air from the smokebox enters the cylinder. With engines using saturated steam this is not a serious matter, as the temperatures are not high; but when superheated steam 35 is used the walls of the cylinder are heated to a high enough degree so that the oil adhering to the walls is oxidized by the air admitted and lubrication is destroyed. One of the leading purposes of all so-called drift- 40 ing valves is to prevent this admission of air from the smokebox by supplying enough steam to the cylinder during drifting so that when the exhaust port opens the pressure in the cylinder is about equal to atmospheric 45 pressure. Obviously there is a considerable waste of steam if this is continued after the temperature of the cylinder walls has fallen to a point where oxidation would no longer occur. It is the purpose of the present in- 50 vention to obviate this waste.

This object is attained by the mechanism illustrated in the accompanying drawings, in which—

Figure 1 represents in outline a locomo-

tive with the device attached; Fig. 2 shows 55 in longitudinal central section one of the valves employed; Fig. 3 shows, partly dia- grammatically, the gage and connected parts with portions of the gage broken away to show the air valve, the latter in section; Fig. 60 4 shows also partly diagrammatically, a modification; Fig. 5 shows the superheater, header, and connected parts, in greater de- 65 tail; Fig. 6 is another modification. It will be evident at a glance that the figures are not all on the same scale.

Referring first to Fig. 1, there is here 70 illustrated the preferred form of my device applied to a locomotive. The locomotive is of any ordinary type equipped with a super- 75 heater, and is not modified for the present purpose as far as its structure is concerned. In other words, my device can be applied directly to any existing or new superheater locomotive without necessitating any modi- 80 fication or redesigning of the locomotive. Steam for my drifting device is taken from the turret 1 or any other convenient or de- 85 sired point, and is carried by pipe 2—2—2 to the superheater header 3. In the pipe 80 line 2—2—2 there are two valves, 4 and 5, which control the steam flow through it. To permit drifting steam to reach the super- 85 heater header both these valves must be open, the closing of either interrupting the flow completely. Both of the valves operate in response to certain conditions in steam pipe 6, as will presently be explained.

The steam flowing through line 2—2—2 90 is delivered by it to the "saturated" side 7 of the superheater header, shown more clearly in Fig. 5. In this figure there is 95 illustrated on an enlarged scale the superheater header 3 and the connected parts as far as they are of interest for the present purpose. This header and the superheater shown are of the usual type, which is practically standard, and is well known to any one skilled in this art. The header shows the 100 usual two chambers 7 and 8, to the former of which steam is delivered in the usual way by the drypipe 9. The superheater elements or units 10 lie in the enlarged flues 11, their ends connected with and opening into the two chambers 7 and 8. Two steam 105 pipes 6 lead from chamber 8 to the steam chests 13, only one steam pipe and steam chest being visible in the drawing. In the

ordinary operation of the locomotive when the engineer opens the throttle steam passes from steam pipe 9 to chamber 7, thence through units 10 where it is superheated by 5 the hot gases flowing through the flues 11, thence to chamber 8, and thence to the steam chests 13 to be admitted to the cylinders 14 by the distribution valves in the steam chests. 35 is the usual damper which 10 controls, automatically or otherwise, the flow of hot gases through the flues containing the superheater units.

Referring now again to Fig. 1, a pipe 15 is seen to lead from steam pipe 6 to the 15 lower part of valve 5. This valve, shown on a larger scale in Fig. 2, is seen to be a differential piston valve. Steam pressure coming from steam pipe 6 through pipe 15 acts on the lower face of piston 16 in opposition to steam pressure from the turret coming through pipe 2 and acting on the surface 17. In its upper position, shown in Fig. 2, the valve shuts off communication between ports 18 and 19, while when the 25 valve is in its lower position, these ports are open.

The valve 4 is responsive to temperature in the steam pipe. 21 is the bulb of a pressure pyrometer of a well known type, 22 being the capillary tube connecting the bulb with the indicating instrument 23 in the cab. The bulb and tube are only diagrammatically indicated in Fig. 3. 23 is the indicating instrument. Its pointer 24 swings 30 about center 25 in response to temperature changes of the bulb, thus indicating the temperature on scale 26. As far as just described the instrument is of a wellknown commercial type. The following additional 35 mechanism is provided for the present purpose. The pointer 24 carries a cam or arc 27. This is so arranged that at a certain desired temperature of the bulb 21, it comes into operative contact with the extension 28 40 of valve 29, opening the valve. When the arc 27 is out of contact with extension 28, spring 30 closes this valve. This valve 29 controls an air line 31, running, as will be seen from Fig. 1, from the air tank 32 45 through the indicating instrument 23 to the valve 4. 33 is a reducing valve, bringing down the pressure of the air from the air tank to about twenty five pounds per square inch. The valve 4 is one of the type 50 operated by compressed air and may be of usual construction. When valve 29 is in open position, compressed air is carried to valve 4 and opens it. When valve 29 is closed by spring 30, the reduced portion 34 55 of extension 28 lies in the opening through the valve casing and permits the escape of the air in that portion of pipe 31 leading to valve 4. Valve 4 will then automatically close.

60 65 The operation of this device will now be

readily understood. Let us first assume that the engine is under way, the throttle being open. Steam is flowing through the dry pipe to the header, through the superheater units, back to the header, through the steam 70 pipes, to the main distribution valves. Pressure from the steam pipe keeps valve 5 closed. The steam flowing through the steam pipes is superheated, and its temperature is such as to bring the pointer 24 over 75 to some such position as shown in Fig. 3, and valve 29 is open, which in turn allows air from tank 32 to reach valve 4 and hold it open. Steam flow through pipe 2 is, therefore, at such times permitted as far 80 as valve 4 is concerned, but is shut off by valve 5.

If now the main throttle is closed and the engine continues to run, as on a down grade, the main engine cylinders work like a 85 pump, at least partially pumping out what steam is left in the system comprising dry pipe, superheater, and steam pipe. After some strokes of the piston the pressure in steam pipe 6 will be so reduced that valve 90 5 will no longer be held shut by pressure on the lower side of piston 16 and will go to its lower position. This at once establishes communication between steam turret 1 and header 3, through pipe 2, since valve 4 is also 95 open. Steam now flows through pipe 2 to the chamber 7 of the header, and thence by the usual route to the steam chest. This drifting steam will reach the steam pipe in a superheated state, as the superheater units 100 retain their heat for some time after the damper 35 is closed. The flow of the drifting steam however gradually cools off the superheater units, since they are receiving no additional heat from without, and when 105 the temperature is lowered to a pre-determined point, valve 29 and as a consequence valve 4 will close, and no more drifting steam will be supplied. The point at which valves 29 and 4 are to close is taken so that 110 the temperature of the drifting steam flowing through the steam pipe, and consequently the temperature of the valve chest and cylinder walls which closely follows that of the drifting steam, is low enough so that 115 no harm will result even if air from the smokebox enters the cylinders. This, as above pointed out, will be in the neighborhood of the temperature of saturated steam of corresponding pressure, though the exact 120 point will be experimentally determined in practice.

As soon as the main throttle is again opened, valve 5 will be shut off by pressure from the steam pipe, and in response to the 125 rising temperature of bulb 21 due to the flow past it of the superheated steam, valve 4 will again open, and conditions are as in the first place.

While the above described is the preferred 130

form of my device certain modifications are evidently possible, such as are illustrated in Figs. 4 and 6.

In Fig. 4 the valve 4 is shown operated by 5 electrical means. The hand 24 instead of actuating a valve makes contact with two points 36—36 thus completing the circuit through battery 37 and electromagnet 38. When this circuit is completed and magnet 10 38 energized its armature 39 is attracted and valve 4 opened. When contact 36 is broken the valve closes by its own weight. The other parts of the device are as described above.

15 In the modification of Fig. 6 the pressure pyrometer and indicator are replaced by an electrical pyrometer. This may be, and is here shown as, of usual construction. The "hot" couple 40 is located in the steam pipe, 20 leads 41—41 connecting it with the binding posts 42—42. The details of the instrument are not illustrated, as they form no part of the present invention. In response to a rise in temperature of the "hot" end 40, the 25 pointer 43 swings toward the right. The arrangement is such that when it has swung to the desired position, and as long as it remains there, the bar 44, carried by pointer 43, contacts with the two points 36, and completes the circuit through battery 37 and coil 30 38, actuating armature 39 and opening valve 4.

By the substitution of the electrical means the principle of the device is not altered in 35 any way. The valve 4 is opened and kept open when and as long as the steam flowing through pipe 6 is above a predetermined temperature. When this temperature is below this point the valve closes. The operation of the device as a whole is in effect the same as described above in connection with the preferred form.

It will be evident that other modifications are possible. The above is to be taken as 45 illustrative of my device, the invention being that the following claims shall include and cover all variations coming within their spirit.

What I claim is:

50 1. In a locomotive equipped with a super-

heater, and having a cylinder, a valved conduit adapted to supply steam to the superheater, a second conduit adapted to convey steam from the superheater to the cylinder; the combination of a by-pass from the steam 55 space of the locomotive to the superheater, and a valve in said by-pass responsive to the temperature of the second mentioned conduit.

2. In a locomotive equipped with a super- 60 heater, and having a cylinder, a valved conduit adapted to supply steam to the superheater, a second conduit adapted to convey steam from the superheater to the cylinder; the combination of a by-pass from the steam 65 space of the locomotive to the superheater, a valve in said by-pass and automatic means to open it when the steam flowing through the second conduit is at or above, and to close it when it is below, a predetermined 70 temperature.

3. In a locomotive equipped with a super- 75 heater, and having a cylinder, a valved conduit adapted to supply steam to the superheater, a second conduit adapted to convey steam from the superheater to the cylinder; the combination of a by-pass from the steam 80 space of the locomotive to the superheater, and two valves in said by-pass acting in response respectively to the temperature conditions and to the pressure conditions in said second conduit.

4. In a locomotive equipped with a super- 85 heater, and having a cylinder, a valved conduit adapted to supply steam to the super- 90 heater, a second conduit adapted to convey steam from the superheater to the cylinder; the combination of a by-pass from the steam space of the locomotive to the superheater, a valve in said by-pass, automatic means to open it when the steam flowing through the second conduit is at or above, and to close it when it is below, a predetermined temperature, a second valve in said by-pass, and automatic means to open it when the pressure in the second conduit is below, and to close it when it is at or above, a predetermined 95 point.

RUDOLF M. OSTERMANN.
